CHAIR-DESK OR THE LIKE

Dave Chapman, Chicago, and Kim Yamasaki, Lombard, Ill., assignors to Brunswick Corporation, Chicago, Ill., a corporation of Delaware

Filed Dec. 21, 1961, Ser. No. 68,003

Term of patent 14 years

(Cl. D33—11)

Fig. 1.

Fig. 2.

FIG. 1 is a perspective view of a chair-desk showing our new and ornamental design;

FIG. 2 is a side elevational view thereof;

FIG. 3 is a top perspective view thereof; and

FIG. 4 is a front perspective view thereof.

The design is characterized by a generally horizontally disposed desk top in the form of a trapezium including a front edge approximately parallel to the chair seat, a side edge at substantially right angles to the front edge, an opposite side edge extending rearwardly and laterally outwardly from the front edge at a pronounced angle and a rear edge extending laterally from the first side edge and slightly forwardly to the opposite side edge and being concavely curved, the corners of the top except at the juncture of the last two mentioned edges being softly

rounded and the corner at the juncture of the last two edges being boldly rounded.

We claim:

The ornamental design for a chair-desk or the like, substantially as shown and described.
